Underwood, Cynthia R.; Notice of Allowance for U.S. Patent Application No. 29/623,900; United States Patent and Trademark Office; Alexandria, Virginia; date mailed Sep. 12, 2018.

Primary Examiner — Cynthia R Underwood(74) *Attorney, Agent, or Firm* — Thomas E. Lees, LLC(57) **CLAIM**

The ornamental design for a teach pendant bumper, as shown and described.

DESCRIPTION

FIG. 1 is a perspective view of a teach pendant bumper; FIG. 2 is a left side elevational view of the teach pendant bumper;

FIG. 3 is a right side elevational view of the teach pendant bumper;

FIG. 4 is a rear side elevational view of the teach pendant bumper;

FIG. 5 is a front side elevational view of the teach pendant bumper;

FIG. 6 is a top plan view of the teach pendant bumper; and, FIG. 7 is a bottom plan view of the teach pendant bumper. The broken lines represent portions of the structure that forms no part of the claim.
